(57) **CLAIM**

The ornamental design for a duffel bag, as shown and described.

DESCRIPTION

FIG. 1 shows a front perspective view of a duffel bag; FIG. 2 shows a front elevation view of the duffel bag of FIG. 1;

FIG. 3 shows a rear elevation view of the duffel bag of FIG. 2;

FIG. 4 shows a right elevation view of the duffel bag of FIG. 1;

FIG. 5 shows a left elevation view of the duffel bag of FIG. 1;

FIG. 6 shows a top view of the duffel bag of FIG. 1; and, FIG. 7 shows a bottom view of the duffel bag of FIG. 1. The broken lines in FIGS. 1-7 illustrate the environment of the duffel bag and form no part of the claimed invention.

1 Claim, 7 Drawing Sheets
